Primary Examiner — Clare E Heflin(74) *Attorney, Agent, or Firm* — Frost Brown Todd LLC;
Dennis S. Schell(57) **CLAIM**The ornamental design for a tapered LED light fixture,
substantially as shown and described.**DESCRIPTION**

FIG. 1 is a bottom-left perspective view of the new design;
FIG. 2 is a top-left perspective view of the new design;
FIG. 3 is a top-rear perspective view of the new design;
FIG. 4 is a bottom view of the new design;
FIG. 5 is a top view of the new design;
FIG. 6 is a front view of the new design;
FIG. 7 is a rear view of the new design; and,
FIG. 8 is a right side view of the new design.
The broken lines shown in the drawings are for the purposes
of illustrating portions of the article that form no part of the
claimed design. The left side view is a mirror image of the
right side view (FIG. 8) and is therefore omitted.

1 Claim, 7 Drawing Sheets(56)
